DEVICE EMPLOYING ELECTRONIC TUBES

Paul Kapteyn, Berlin, Germany, assignor to
Radioaktiengesellschaft D. S. Loewe, Berlin-
Steglitz, Germany, a company of Germany

Application June 24, 1933, Serial No. 677,525
In Germany June 24, 1932

1 Claim. (Cl. 179—171)

For operation of devices operating with electronic tubes, more particularly receiving devices, the magnitude and constancy of the operating potentials is of more or less great importance in the different stages of the arrangement. Of large influence, for example, is the magnitude of the anode potential in those stages of the device from which a regenerative energy is taken, as by a decrease of the anode current the back-coupling is considerably affected, and it may even occur, that the working condition is no longer such as to maintain the oscillations.

The invention has for its object to eliminate disturbances of this nature caused by undesirable variations in the anode current and sets forth means by which the anode current, even upon variations in the operating potentials, may be maintained constant insofar as this may be desirable or necessary.

Particularly important is the invention for apparatus which are intended for connection with different kinds of current and potentials.

According to the invention it is for instance possible to build receivers which may be connected as desired with a direct-current or an alternating-current supply of any used potential (100—200 volts) whereby only the series resistance of the heating-circuit has to be changed.

According to the invention the grid bias for stages, the anode current of which has to remain constant, may be taken from resistances, which are directly connected to the anode-current-source, or are traversed by the anode-current of the final stage, i. e. in which the current is varying approximately in proportion to the potential of the supply. In the stages to be adjusted consequently the anode potential and the grid bias are varying practically proportional to the potential of the supply.

Now, according to the invention, the problem has to be solved to keep the anode current constant under these circumstances.

When

45 J_a is the anode-current

E_g is the grid-bias potential

E_a is the anode potential of the valve

m is the amplification factor of the valve

K is a constant,

50 there exists, as well known, the equation:

$$J_a = K \left(E_g + \frac{E_a}{m} \right)$$

55 According to this formula it seems to be im-

possible to solve the problem; nevertheless there exists a solution in the case that

$$E_g = - \frac{E_a}{m}$$

i. e. that the grid bias is equal or approximately equal to the quotient of the anode potential to the amplification factor of the valve. At this point of the characteristic the current J_a is, in contradistinction to the formula, not zero owing to the fact that besides the voltages

$$E_g \text{ and } \frac{E_a}{m}$$

there is a third voltage effective, namely the starting potential of the electrons i. e. the grid potential at which the anode potential begins to flow which is independent of the anode-potential.

Naturally this low voltage is able to produce small anode-currents only.

In order to obtain sufficient effects it is therefore necessary to use valves of a high amplification factor (30 or more) and very high anode resistances. Under this condition the effective control voltage depends to only a very small degree upon the anode voltage of the valve itself, and very low negative grid bias (at the ordinary supply voltages less than 2,5 volts, preferably 0,5 volts) has to be used.

Grid currents may be avoided by using valves producing such currents at a positive or very low negative grid potential only; valves in which the support of the emissive cathode material is made of tungsten have the desired property.

In any case caution has to be taken that in the case of the most positive grid bias occurring detrimental grid current is just precluded, whilst even in the case of the most negative grid bias occurring a grating noise (as sometimes produced by the back-coupling) does not take place.

A circuit diagram for a form of embodiment of the invention is illustrated in the drawing. This embodiment shows a two valve wireless receiver for immediate connection with an A. C. supply operated without a transformer. The tubes 1 and 14 and the rectifier tube 20 possess indirectly heated cathodes. The filaments 2, 15 and 21 are connected in series with a preferably adjustable series resistance 19 with the A. C. mains terminals 24, 25.

The grid circuit 6, 7 is connected with the grid 4 of the first tube and coupled with the aerial circuit 10 and the back-coupling circuit 8, 9. 11 is the anode resistance of the first tube, 12 the coupling condenser between the two tubes, and 13 the

grid leak resistance of the second tube. In the anode circuit there is situated the resistance filter 33, 34, 35, which is connected on the one hand with the cathode 22 of the rectifier tube and on the other hand with the anodes 18 and 5 of the two tubes 14 and 1 by means of the loudspeaker 36, or the filter resistance 32 and anode resistance 11.

The cathodes 3 and 16 of the two tubes are connected with each other and in A. C. fashion by filter combinations 26, 27, 28, 29, 30, with the one side of the supply, whereby the resistances 26, 27 serve for producing the grid biases.

I claim:

An arrangement comprising a plurality of 15 electron valves with anode, grid, and cathode, an input circuit, an output circuit, an anode current source, and means for coupling said valves with each other, the first of said valves having a

high amplification factor of more than 30, the grid of said first valve connected over said input circuit with a resistance capacity combination for effecting a negative potential on this grid relative to the cathode of this valve, said resistance-capacity combination included in the anode circuit of the final power amplifier valve on the cathode side for producing a voltage drop forming said negative potential of the grid of said first valve equal to the quotient of the potential of said anode-current-source and the amplification factor of said first valve, said resistance capacity consisting of a resistance connected through a second resistance to the negative pole of the supply, a condenser being connected in parallel to said two resistances, 15 the input circuit of said first valve connected to the connection point of said resistances.

PAUL KAPTEYN.
